UNITED STATES PATENT OFFICE.

CHARLES H. LYON, OF GREELEY, KANSAS.

MACHINE FOR MEASURING AND WINDING FABRICS.

SPECIFICATION forming part of Letters Patent No. 352,478, dated November 9, 1886.

Application filed July 2, 1886. Serial No. 206,923. (Model.)

To all whom it may concern:

Be it known that I, CHARLES H. LYON, a citizen of the United States, residing at Greeley, in the county of Anderson and State of 5 Kansas, have invented a new and useful Improvement in Machines for Folding and Measuring Fabrics, of which the following is a specification, reference being had to the accompanying drawings.

10 This invention relates to improvements in machines for winding and measuring goods of any width, from the narrowest ribbons to the widest of any goods, all of which will be hereinafter more fully described, and pointed out 15 in the claims.

In the accompanying drawings, forming part 20 of this specification, Figure 1 is a perspective view of the machine having a part broken away. Fig. 2 is a vertical transverse section on $x x x$ of Fig. 1. Fig. 3 is a longitudinal vertical section on $y y$ of Fig. 1. Fig. 4 is 25 an enlarged view showing the manner of holding the board or block on which the fabric is wound. Fig. 5 is an elevation of the gearing for indicating the length of the goods. Fig. 6 is a perspective view of one of the clamps. Fig. 7 is a side view of a forked holder or center. Fig. 8 is a longitudinal vertical section of a part of the top frame, A'' , showing the 30 friction-cap over one of the centers at $Z Z$, Fig. 1.

$A A$ is the bed-frame of the machine.

$A' A'$, &c., are the corner-posts.

$A'' A''$ are the top frames at the end.

35 A''' is the side top frame.

B is the opposite sliding or adjustable beam, having a tenon, b , at each end, which slides in the grooves b' in the sides of the end top frames, $A'' A''$.

40 C is an adjusting-rod screw-threaded in its entire length, having a handle, c , and the nut c' , formed like a yoke, and which nut is secured to the inside of the sliding beam B . The screw-rod C passes through the nut c' , and also through

45 a nut, b'' , on the outside of the sliding beam B . The free end of the rod C is supported in a strong flat vertical bar, D , which is sustained on the standard D' , projecting above the bed-frame A . On the opposite side of the frame is 50 a similar standard, D'' . In these standards D' D'' are pivoted two rollers, $E E'$. The lower

roller, E , has no vertical adjustment in its bearings; but the top roller, E' , is pivoted in vertical slotted bearings e'' in the standards, to admit of a slight vertical adjustment, and 55 on top of each journal is a coiled spring, d , which is operated upon by a thumb-screw, d' , inserted in the top of each standard through a fixed nut, d'' , so that the top roller, E' , can be forced down close upon the bottom roller, E , for a purpose which will be hereinafter explained. On the inner end of the bottom roller, E , is a journal, h , which projects some distance through the standard D'' , on which journal is a pinion-wheel, e , which meshes with cogs under a wheel, F . On the same shaft, F' , of the wheel F is a pinion, f , which meshes with a spur-wheel, G , and on the shaft G' is a pinion, g , which meshes with a spur-wheel, H , and on the top of the shaft H' is an index, h' , and 65 around it are the graduations to indicate the yards or feet.

70 $I I'$ are forked cramps of metal having in their shanks holes i for the thumb-screws $J J'$, which work in nuts i' on the side of the sliding beam B , their ends being pointed for penetrating the ends of the boards or blocks $M M'$, upon which the goods are wound and unwound.

75 Passing through the top beam, A'' , are forked centers or holders $K K'$, having their outer ends screw-threaded. On the end of K is a crank-handle, k , for operating the machine. On K' is a handle, k' , for tightening and adjusting the center K' through the beam A'' . On top of the beam A'' is a thumb-screw, a'' , for 80 tightening the center K' by means of a friction cap, s , over the journal of center K' , and inside of the top frame, A'' , as seen in Fig. 8 in section.

85 The adjusting sliding beam B can be moved 90 in or out by means of the screw-rod C , so as to bring the screws $J J'$ and cramps $I I'$ up to the ends of the boards or blocks $M M'$, on which the goods are to be wound up or from which to be unwound.

95 The operation of the machine is as follows: The particular fabric is placed as represented by M' in Figs. 1 and 3. The sliding beam B is then, by means of screw C , so adjusted that the points of the thumb-screw $J J'$, Fig. 100 4, will be inserted in the ends of the boards or blocks $M M'$. The clamps or centers $K K'$ are

then adjusted to the other ends of said boards or blocks by means of the handles $k k'$. The thumb-screws $J J'$ and centers $K K'$ are then tightened to securely hold the two blocks, 5 which are prevented from turning on the center-points by the use of the cramps $I I'$, through which the screws $J J'$ loosely revolve in the center hole, i , Fig. 6. The loose end of the fabric on the board M' is then carried over the 10 top roller, E' , around and under it, and over and around the bottom roller, E , and to and around the board M , where it is fastened to the board, all of which is illustrated in Fig. 3 and the direction indicated by the arrows. 15 The screws $J J'$ and centers $K K'$ are so regulated that, in connection with the sliding beam, any length of board or ribbon-block can be held between them very securely. The screws $d' d'$ on top of the standards $D D'$ work in the 20 fixed nuts d'' and press upon coiled springs d , which springs rest upon the journal-bearings of the upper roller, E' . By means of the screws d' , therefore, the upper roller, E' , can be pressed down upon the lower roller, E , which is fixed 25 in its bearings to any degree, whereby such a tension can be given to the fabric running between them as to wind the fabric as tightly

upon the board M as may be required. The journal h at one end of the lower roller, E , is extended through the standard D'' , and on its 30 end is a pinion, e , which drives the gearing $F G H$ and the indicator-arm h' , for the purpose of indicating the exact number of yards wound upon the board M . The crank-handle k on the center K gives motion to every part of the machine. 35

I claim—

1. The combination of the rollers $E E'$, the boards $M M'$, the centers $K K'$, cramps $I I'$, tightening-screws $J J'$, and adjustable beam B , substantially as described. 40

2. The combination of the frame A'' , the centers $K K'$, with handles $k k'$ for adjustment, and tightening-screw a'' , the screw-rod C , with its handle c , yoke-nut c' , the sliding beam B , 45 with its tenons, cramps $I I'$, and screws $J J'$, and grooved end beams, A' .

In testimony that I claim the foregoing as my own I hereto affix my signature in presence of two witnesses.

CHAS. H. LYON.
